UPRIGHT BLOCK DESIGNING AND HANDLING APPARATUS

Arthur James Storer, Mackay, Idaho

Filed Apr. 11, 1960, Ser. No. 21,185

5 Claims. (Cl. 35—73)

The present invention relates generally to educational or display means and more particularly to upright block designing and handling apparatus.

The primary object of this invention is to provide block designing apparatus which can be used as an educational toy or for display purposes and utilizes a number of flat, decorative blocks which may be arranged in many different patterns or configurations on a specially adapted board.

Another object of this invention is to provide block designing apparatus in which the block carrying board has means for positively holding each block and can be used in an upright or near upright position without displacement of any blocks.

Another object of this invention is to provide block designing apparatus including a scoop, cooperating blocks and a board, each being of special form, the board being grooved to permit the use of the specially designed scoop for rapid removal of the cooperating blocks, one row at a time, without disturbing the remainder of the blocks.

Finally, it is an object to provide block designing apparatus of the aforementioned character which is simple and convenient to use and which will give generally efficient and durable service.

With these and other objects definitely in view, this invention consists in the novel construction, combination and arrangement of elements and portions, as will be hereinafter fully described in the specification, particularly pointed out in the claims, and illustrated in the drawings which form a material part of this disclosure, and in which:

Figure 1 is a perspective view of the board with blocks in place and the scoop in use;

Figure 2 is an enlarged fragmentary sectional view taken on the line 2—2 of Figure 1;

Figure 3 is a sectional view taken on the line 3—3 of Figure 1;

Figure 4 is an enlarged sectional view taken on the line 4—4 of Figure 3; and

Figure 5 is a side elevation view, on a reduced scale, showing the board supported in near upright position.

Similar characters of reference indicate similar or identical elements and portions throughout the specification and throughout the views of the drawings.

The apparatus includes a board 10, which will be considered as normally disposed in near vertical position, of any suitable size and material according to requirements and a plurality of blocks 12, with substantially flat underside surfaces, which are illustrated as rectangular in shape although other shapes may be used. The board 10 has a plurality of block supporting hangers 14 projecting from the front face thereof, said hangers being arranged in vertical rows and spaced apart a distance equal to the height of one block 12. The hangers 14 are preferably generally wedge shaped and have upwardly sloping lips 16.

Each block 12 has a chamfered upper edge 18 sloping

2

downwardly and rearwardly from the front face 20 and is provided with a socket 22 adjacent the upper edge in the rear face of the block, said socket having an angularly disposed upper face 24 to correspond with the slope 5 of a hanger lip 16, so that the block lies flat against the board when supported by a hanger, as in Figure 2. The front faces 20 of blocks 12 may be decorated in any suitable manner with patterns, numbers, letters, or other characters which can be arranged in various configurations. Lettered blocks can be used for spelling as an educational toy, or numbered blocks may be used for mathematical training. Alternatively, various colored or patterned blocks can be arranged artistically for display purposes.

15 For maximum visibility and ease of use, the board 10 may be supported by an easel 26, of any suitable type, in a near upright position, as in Figure 5. For more permanent use, the board can be mounted directly on a wall or other supporting surface.

20 The board as illustrated is small and carries relatively few blocks, but the apparatus is intended for use in large sizes with many blocks. One problem in such large sizes is the removal of a large number of blocks when changing the arrangement. For this purpose, a scoop 30 is 25 used which cooperates with the board 10 and utilizes the specific block design and means of support for ease of removal.

The scoop 30 comprises a generally rectangular casing 32 having an open upper end 34 and being dimensioned 30 to hold a plurality of blocks 12 in stacked relation. Fixed to the bottom panel 36 of casing 32 are two longitudinal runners 38 having tapered guide ramps 40 extending beyond the open end 34. The board 10 is provided with vertical pairs of grooves 42 spaced on opposite 35 sides of each vertical row of hangers 14, the runners 38 being freely slideable in said grooves and being of sufficient depth to hold the bottom panel 36 slightly above the front faces 20 of the blocks when the runners are seated in the grooves.

40 When the scoop 30 is moved upwardly with the runners 38 in one pair of grooves 42, the guide ramps 40 lift each block 12 outwardly and into the casing 32, as in Figure 4. The chamfered edge 18 of each block 12 allows the block to move outwardly and off its hanger 45 14 without disturbing the next block above. With one sweeping action an entire row of blocks can be removed, this being a very useful factor with large block displays which would otherwise be removed individually by hand. Also, the collected blocks remain in a neat stack when 50 emptied from the scoop.

To avoid displacement of blocks on either side of those being removed, the scoop 30 is provided with retaining fingers 44 projecting forwardly and laterally outwardly of the open end 34, generally planar with the bottom 55 panel 36, so as to ride just above the blocks 12 on either side of the scoop. Thus the blocks immediately adjacent the block being removed are prevented from lifting away from the board. For simplicity, the fingers 44 may be made unitary with the bottom panel 36, or can be made 60 separately and fixed in place by suitable means.

With this apparatus, many designs and arrangements of blocks can be quickly set up in any order or position on the board and can be even more quickly removed by scooping directly from the board. Many different materials may be used for the board, blocks and scoop, such as metal, wood, or plastic, depending on the size and particular use of the apparatus.

65 The operation of this invention will be clearly comprehended from a consideration of the foregoing description of the mechanical details thereof, taken in connection with the drawings and the above recited objects.

70 It is understood that minor variation from the form

of the invention disclosed herein may be made without departure from the spirit and scope of the invention, and that the specification and drawings are illustrative rather than limiting.

I claim:

1. Upright block designing and handling apparatus, comprising: a generally flat board having a plurality of individual block supporting means on one face thereof and arranged in spaced rows; a plurality of blocks each having means to engage one of said block supporting means; said board having grooves in said one face adjacent to and extending parallel to said block supporting means; a scoop having runners engageable in said grooves to guide the scoop along said rows; said runners having forwardly extending, tapered ramp portions to engage and lift said blocks from said block supporting means into the scoop.

2. Upright block designing and handling apparatus, comprising: a generally flat board having a plurality of individual block supporting means on one face thereof and arranged in spaced rows; a plurality of blocks each having means to engage one of said block supporting means; said board having grooves in said one face adjacent to and extending parallel to said block supporting means; a scoop having runners engageable in said grooves to guide the scoop along said rows; said runners having forwardly extending, tapered ramp portions to engage and lift said blocks from said block supporting means into the scoop; and fixed finger elements extending forwardly and laterally of said scoop and disposed to pass closely over the blocks laterally adjacent to those entering said scoop, thereby preventing displacement of the adjacent blocks.

3. Upright block designing and handling apparatus, comprising: a board having block supporting means on one face thereof; a plurality of blocks each having means to engage said block supporting means; said board having grooves in said one face adjacent to said block supporting means; a scoop having runners engageable in said grooves to guide the scoop; said runners having forwardly extending, tapered ramp portions to engage and lift said blocks from said block supporting means into the scoop.

4. Upright block designing and handling apparatus, comprising: a generally flat board having a plurality of individual block supporting means in rows on one face thereof; said block supporting means being hangers and having upwardly sloping lip portions; a plurality of substantially flat blocks each having a socket to engage one of said hangers; said sockets having angularly disposed faces to fit said lip portions, whereby said blocks are suspended flat against said board; said board having grooves in said one face adjacent to and extending parallel to said block supporting means; a scoop having runners engageable in said grooves to guide the scoop along said rows; said runners having forwardly extending, tapered ramp portions to engage and lift said blocks from said block supporting means into the scoop.
5. Upright block designing and handling apparatus, comprising: a generally flat board having a plurality of individual block supporting means in rows on one face thereof; said block supporting means being hangers and having upwardly sloping lip portions; a plurality of blocks each having a substantially flat underface and a socket in said underface to engage one of said hangers; said sockets having angularly disposed faces to fit said lip portions, whereby said blocks are suspended flat against said board; the upper edge of each of said blocks being angularly downwardly chamfered toward said board; said board having grooves in said one face adjacent to and extending parallel to said block supporting means; a scoop having runners engageable in said grooves to guide the scoop along said rows; said runners having forwardly extending, tapered ramp portions to engage and lift said blocks from said block supporting means into the scoop.
